United States Patent Office

Des. 185,390
Patented June 2, 1959

185,390

NAPKIN DISPENSER

Roy C. Rhyner, Menasha, Wis., assignor to Wisconsin
Tissue Mills, Menasha, Wis., a corporation of Wisconsin

Application November 10, 1958, Serial No. 53,309

Term of patent 14 years

(Cl. D44—24)

Fig. 1 is a view in perspective of a napkin dispenser embodying my new design.

Fig. 2 is a top plan view of the napkin dispenser.

Fig. 3 is a view in front elevation of the napkin dispenser, the rear elevation being similar.

Fig. 4 is a view in side elevation of the napkin dispenser.

Fig. 5 is a view taken in section on the line 5—5 of Fig. 3.

I claim:

The ornamental design for a napkin dispenser, substantially as shown and described.
